UNITED STATES PATENT OFFICE.

GRANT BARNHART, OF CLEVELAND, OHIO.

DESIGN FOR A SALT AND PEPPER CRUET.

SPECIFICATION forming part of Design No. 29,966, dated January 10, 1899.

Application filed September 30, 1898. Serial No. 692,346. Term of patent 7 years.

To all whom it may concern:

Be it known that I, GRANT BARNHART, a citizen of the United States, residing at Cleveland, in the county of Cuyahoga and State of Ohio, have invented and produced a new and original Design for a Salt and Pepper Cruet; and I do hereby declare the following to be a full, clear, and exact description of the same, reference being had to the accompanying drawings, forming a part thereof.

This invention relates to a new and original design for salt and pepper cruets, and has for its object to provide a design of this character which shall be both useful and ornamental.

The leading feature of the design resides in a cruet having a square pyramidal base merging into a cubical body, which terminates in a shoulder with upwardly-tapering sides merging into a cylindrical neck, the side of said cruet having the representation of a ship thereon.

A minor feature of the design resides in the top of the cruet, which is circular and provided with a series of openings, the openings on one side of the top being of greater diameter than those on the other side.

In the accompanying drawings, forming a part of this specification, Figure 1 is a side

elevation of a salt and pepper cruet embodying the herein-described design, and Fig. 2 is 30 a top plan view thereof.

Referring to the drawings, the numeral 1 designates a cruet comprising a square pyramidal base 2, the sides of which merge into the cubical body at 3, and 4 represents a shoulder in the shape of a truncated cone, with its lower edges merging with the body and its upper edges merging with the cylindrical neck 5.

Upon the side of the cruet is the representation of a ship.

The top of the cruet (designated by the numeral 6) is circular and provided at one of its sides with a series of openings 7 and at its other side with a similar series of openings 8 45 of a smaller diameter than openings 7.

What I claim is—

The design for a combined salt and pepper cruet substantially as herein shown and described.

In testimony whereof I affix my signature in presence of two witnesses.

GRANT BARNHART.
